THREAD ROLLING

James W. Batchelder, Alstead, N. H., assignor to
 Jones & Lamson Machine Company, Springfield, Vt., a corporation of Vermont

Application February 23, 1944, Serial No. 523,549

14 Claims. (Cl. 80—6)

1

The present invention relates to the art of thread rolling, and more particularly to thread rolling machinery employing a plurality of circular thread rolling dies for rolling a work blank therebetween to produce threads thereon.

It is a principal object of this invention to simplify the operation of phasing the circular thread rolling dies relative to one another so that the threads produced on the work at the point of thread rolling contact will be properly formed in relation to the preceding threads rolled on the work as the dies and work are rotated.

It is also an object of this invention to provide a thread rolling die and spindle construction which will facilitate the quick application and interchangeability of thread rolling dies to the spindle of a multiple spindle thread rolling machine and which will assure accurate phase relationship between threads of the thread rolling dies thus applied.

In accordance with the present known principles of thread rolling machines wherein circular thread rolling dies are used to roll threads on a work blank positioned at a point between the peripheries of the dies, it has been necessary to disconnect at least one of the spindles on which a thread rolling die is mounted from the gearing and transmission mechanism connecting the spindles together in order that the angular position of one of the thread rolling dies may be adjusted relative to the others so that the threads on the periphery of the dies at the point of thread rolling contact will be in proper phase relation with each other. Alternatively, the dies may be moved axially of each other to obtain the proper phase relation. This phase relationship may be explained by observing that as the work rotates past the point of thread rolling contact during the thread rolling process, the groove previously formed on the work by the thread rolling die must line up exactly with the thread of the die at the succeeding point of thread rolling contact on the work. Varying the angular or axial position of one die relative to another to bring the dies to this relationship is called phasing. The present type of thread rolling machines which are provided with members capable of disconnection for the purpose of revolving one die spindle with relation to another so as to phase the dies are not entirely satisfactory since this operation must be conducted on a cut and try basis, and it is therefore, difficult to obtain in this manner the exact phasing of the dies required for precision thread rolling. This invention there-

2

fore, contemplates the provision of keyways in the spindle bore of the circular thread rolling dies which will cooperate with key seats and keys on the spindles of the thread rolling machine to insure that the thread rolling die is always placed on the spindle in the same desired angular relationship. Since the spindles are permanently geared together in constant ratio with the key-seats on the spindles in a predetermined relation to each other the accurate phasing of the thread rolling dies will be assured after each application of the dies to the spindles.

It is also an object of this invention to provide a thread rolling die and spindle construction having means for determining and accurately phasing the thread rolling dies at the time of application of the dies to the spindle which will be consistently accurate to such an extent as to always assure a much higher degree of precision in thread rolling than heretofore obtained when interchangeably applying the dies to the spindles.

It is a still further object of this invention to provide a circular thread rolling die with a plurality of keyways which will enable the die to be interchangeably applied to any of the spindles of a circular thread rolling machine employing the principle of incommensurable angle thread rolling and which will assure the accurate phasing of the dies thus applied.

30 Further objects and advantages will be readily apparent by referring to the following specification and drawings in which:

Figure 1 is a transverse section through a plurality of thread rolling dies and spindles embodying the principle of this invention, and also showing in transverse section a pair of work blanks in operative position for incommensurable angle thread rolling with their work centers beneath the common plane of the spindle axes.

40 Figure 2 of the drawings is a view similar to Figure 1 but showing the principle of the invention as applied to the conventional type of thread rolling in which a pair of work blanks are rolled with their work centers in the common plane of the spindle axes.

Figure 3 is a transverse section through the spindles of a thread rolling machine embodying the principle of this invention and showing the gearing for permanently connecting the spindles together in a predetermined and unvarying angular relationship, and also showing means for varying the distance between the centers of the thread rolling spindles for rolling different diameter work blanks.

Figure 4 is a plan view of the circular thread rolling die of this invention and showing in dotted lines the keyway located in a predetermined relation to a point on the thread which may be the thread start on any other predetermined point.

Referring to Figure 1 of the drawings, the invention is shown as applied to a three spindle circular die thread rolling machine in which a pair of work blanks are simultaneously rolled with their work centers positioned at a point beneath the common plane of the spindle axes. This type of thread rolling which is known as incommensurable angle thread rolling, has certain advantages such as automatically compensating for any out-of-roundness developed in the work blank due to the tremendous thread rolling pressure, and unavoidable spiral penetration of the dies into the work. A support (not shown) may be used to position and hold the blanks into thread rolling contact with the dies as is well known in the art. The work blanks 10 and 11 are rolled in contact with the circular thread rolling dies 12, 13, and 14 at the thread rolling contact point 15, 16, 17 and 18 respectively. The thread rolling dies 12, 13, and 14 are located on thread rolling spindles 19, 20, and 21 respectively. The spindles 19, 20, and 21 are provided with keyseats 22, 23, and 24. At the time of the assembly of the machine these spindles whose axes are all located in a common plane are angularly positioned so that their keyseats are all located in parallel axial planes of the spindle axes as shown by Figure 1. The spindles are then permanently geared together by any suitable gearing such as that shown by Figure 3 of the drawings wherein a drive shaft, 25, is provided with worms 26, 27, and 28 in association with worm gears 29, 30 and 31 which are keyed to the thread rolling spindles 19, 20, and 21 respectively. The worms 26 and 28 are slidably keyed to the main drive shaft by means of splines 32 and 33 thus permitting longitudinal movement of the worms 26 and 28 along the shaft 25 so that the spindles 19 and 21 may be moved apart relative to the spindle 20 as will be more fully described hereinafter. With the mechanism thus far described, it will be seen that the thread rolling spindles 19, 20 and 21 are provided with keyways 22, 23, and 24 which are permanently and accurately maintained in a predetermined angular relationship to each other after the machine has been once assembled.

The thread rolling dies 12, 13, and 14 used in the incommensurable angle thread rolling as shown by Figure 1 of the drawings, are each provided with a plurality of thread starts on their threaded peripheries, one of each of which thread starts may be designated by the reference points on each die respectively A, A' and A''. In this case, the work blanks 10 and 11 will have produced, by the rolling process on their peripheries, a thread having a single thread start designated by the points B and B' respectively, and it should be mentioned that the number of thread starts on the circular thread rolling dies is not critical and may be any number so long as they are an integral multiple of the number of thread starts to be produced on the work. To employ the principle of this invention in connection with the incommensurable angle thread rolling being discussed, each of the thread rolling dies must be provided with a number of keyways 40, 41 and 42, identically located on each thread rolling die. Because of the fact that the work centers are beneath the common plane of the spindle axes,

the phase relationship between the dies of each spindle is not identical and therefore the keyways in the die bores for determining this phase relation must be differently angularly located for each spindle, necessitating a number of different keyways equal to the number of spindles of the machine. The keyway 41 is located beneath the thread start point A, A' or A'' and in the axial plane intersecting said thread start point. With 10 the keyway 41 located as described above, it is necessary to locate the other keyways 40 and 42 in their proper angular positions relative to keyway 41 so that the dies may be interchangeably mounted on any of the three spindles of the incommensurable angle thread rolling machine being described. To locate the keyways 40 and 42 in their proper angular position relative to keyway 41, the following formula is used, wherein the angle X in degrees is the incommensurable angle of thread rolling, or what may be otherwise described as the angular displacement of the work center from the common plane of the spindle axis, wherein the angle Y is equal to the angular displacement in degrees of the keyways 40 and 42 from the keyway 41, and wherein S is equal to the 20 number of thread starts on the threaded periphery of the thread rolling die.

$$Y = 2X + \frac{2X}{S}$$

30 Thus it will be seen that the angular displacement in degrees of the keyways relative to each other is a function of the incommensurable angle in degrees and the number of thread starts on the dies.

35 With the keyways 40, 41 and 42 thus located, it is possible to interchange any die 12, 13 or 14 to any of the three spindles shown in Figure 1 by merely observing that the correct keyway in the die bore is in alignment with the keyseat on the spindle to which it is to be applied and if this is done, the dies will always be in proper 40 phase relation with each other. It should be understood that the invention being described is in connection with a circular thread rolling machine in which all of the dies rotate in the same 45 direction.

45 In employing the principle of this invention on a three spindle incommensurable angle thread rolling machine a thread rolling die 13 is placed 50 on the middle spindle 20 with its middle keyway in alignment with the keyseat 23 and locked thereon by means of the key 43. The thread rolling die 12 is then placed on the left-hand spindle 19 with its left-hand keyway 40 in alignment with the keyseat 22 and locked thereon by a key 44. The thread rolling die 14 is then placed on the right-hand spindle 21 with its right-hand keyway 42 in alignment with the keyseat 24 and locked 55 with the key 45. The thread rolling dies are now located on the spindles in the correct angular relation to one another to assure the proper phasing of the threads at the incommensurable thread rolling points of contact.

60 65 Suitable indications such as L, R and M for left, right and middle spindles respectively may be placed on the end of the thread rolling dies to identify the keyways 40, 41, and 42 so that the dies may be interchangeably positioned on any 70 one of the three spindles by merely observing that the proper keyway in the die bore is in alignment with the keyseat on the spindle.

75 By way of illustrating that the phase relationship between the dies has been properly determined by the keyways it should be pointed out

that in the illustration given by Figure 1 the thread rolling point of contact such as shown by 16, is at a point midway between the thread starts 46 and 47 on the die 13 and that the distance on the circumference between the thread start B to be formed on the work 10, and the thread rolling point of contact 16 is equal to the distance on the circumference between the thread rolling point of contact 16 and the thread start 47 of the thread rolling die 13. Likewise, it will be seen that the distance from the thread start A to the thread rolling point of contact 15 is equal to the distance from the thread start B to the point of contact 15.

It should be borne in mind that the keyways 40, 41, and 42 as illustrated and described have been properly located for a predetermined incommensurable angle of thread rolling and if the incommensurable angle is changed such as by varying the diameter of the work without changing the distance between the die axes, the phase relationship between the dies is altered and the keyways must be located in different angular positions as determined by the formula previously described. However, this fact enables a minor precision adjustment of phasing to be made by slightly altering the distance between the die spindle axes to thus slightly alter the incommensurable thread rolling angle or by varying the distance from the common die axes to the work center by a feeding means not shown.

When it is desired to roll different diameters of work it is only necessary to move the die spindles 19 and 21 away from the die spindle 20 to a position such as shown by the dotted lines in Figure 1 which will permit the work of greater diameter shown by the dotted lines to be rolled at the same incommensurable angle shown by the dotted lines. Since the incommensurable angle is not changed, the angular relationship between the thread starts on the thread rolling dies and the keyways is still in correct phase relationship as determined by the formula. Figure 3 of the drawings shows a form of gearing which will permit the movement apart of the thread rolling spindles to vary the spacing between the spindles and thus permit the rolling of different sizes of work diameters at the same incommensurable thread rolling angle.

Thus far, I have described an improved form of die spindle and circular thread rolling die provided with keyseats and keyways which will enable accurate and interchangeable attachment of the dies to the spindles in the proper angular relationship to assure correct phasing of the threads on the dies at the points of thread rolling contact. In the three spindle machine, each die has been provided with three keyways angularly located in relationship to a thread start on the die and the incommensurable angle of the thread rolling. If the invention is to be applied to an incommensurable angle thread rolling machine employing more or less than three spindles it should be readily understood that it is only necessary to have a number of keyways on the circular thread rolling dies equal to the number of spindles. The formula previously described may be used to locate the keyways and this invention is not intended to be limited to a three spindle incommensurable angle thread rolling machine.

Referring to Figure 2 of the drawings, a simplified form of the invention is shown as applied to a more conventional type of thread rolling machine in which the incommensurable angle thread rolling is not used. In this type of machine, the thread rolling blanks 50 and 51 are located with their centers in the common plane

passing through the centers of the spindles 52, 53, and 54. Keyed on the spindles are the circular thread rolling dies 55, 56, and 57. In this conventional type of thread rolling the interchangeable dies are each provided with only one keyway 58 located in a predetermined angular relation to a thread start such as in an axial plane intersecting one of the points of thread start 59. The spindles 52, 53, and 54 are likewise provided with keyseats 60, 61 and 62 which are permanently angularly related at the time of assembly of the machine as previously described in connection with Figures 1 and 3. The thread rolling dies may be locked on the spindles with the keyways in alignment with the keyseats and their proper phase relationship is assured. As previously described in connection with the incommensurable angle thread rolling, the dies are all rotating in the same direction which in this instance, may be counterclockwise. To show that the proper phase relationship has been obtained, it may be pointed out that the distance on the circumference between the thread start 63 of the work 50 and the point of thread rolling contact 64 is equal to the distance on the circumference of the die 56 between the thread start 65 and the point of thread rolling contact 66. Since the keyway on each of the dies 55, 56, and 57 is identically located, any of the dies may be interchangeably mounted on any of the spindles 52, 53 and 54 and the proper phase relationship between the dies and the work will always be obtained. It should be apparent that any number of spindles may be used and this invention should not be construed as limited to the three spindle machine shown by Figure 2 of the drawings.

It may be desirable to employ this invention in connection with a multiple spindle thread rolling machine in which the intermediate dies are of different size than their associated dies. In this instance it is necessary to adjust the gear ratio between the spindles in accordance with the die sizes but so long as the determined ratio is maintained constant during the operation of the machine and assuming the keyseats on the spindles to be angularly located in predetermined relation to each other the correct phasing of the dies will be obtained by observing the principles of this invention.

This invention has disclosed a means of accurately locating the correct angular relationship between a die spindle and a circular thread rolling die to assure proper phasing between a plurality of the dies. By using the principle of this invention the dies may be readily removed and replaced with similar dies without requiring tedious adjustment of the angular relationship of the die spindles to obtain correct phasing.

From the foregoing description of an embodiment of this invention, it should be evident to those skilled in the art that various changes and modifications might be made without departing from the spirit or scope of this invention.

I claim:

1. A circular thread rolling die adapted to be interchangeably applied to the spindles of an incommensurable angle thread rolling machine, said die having a spindle receiving bore therethrough and at least one thread start on its threaded periphery, said bore having a plurality of keyways positioned therein in predetermined angular relations to a thread start, whereby said die may be interchangeably keyed to each one of said spindles in a predetermined angular rela-

tion to said thread start to assure proper phasing of the dies on the machine.

2. A circular thread rolling die adapted to be interchangeably applied to the spindles of an incommensurable angle thread rolling machine, said die having a spindle receiving bore therethrough and at least one thread start on its threaded periphery, said bore having a plurality of keyways positioned therein in predetermined angular relations to a thread start, one of said keyways being angularly located in relation to a thread start, the others of said keyways being angularly displaced in relation to said first mentioned keyway by an amount which is a function of the incommensurable thread rolling angle and the number of thread starts on the die, whereby said die may be interchangeably keyed to each one of said spindles in the predetermined angular relation to said thread start to assure proper phasing of the dies on the machine.

3. A circular thread rolling die adapted to be interchangeably applied to the spindles of an incommensurable angle thread rolling machine, said die having a spindle receiving bore therethrough and at least one thread start on its threaded periphery, said bore having a plurality of keyways positioned therein in predetermined angular relations to a thread start, one of said keyways being angularly located in relation to a thread start, the others of said keyways being angularly displaced in relation to said first mentioned keyway and each other, the angular displacement in degrees being equal to the sum of twice the incommensurable thread rolling angle in degrees plus twice the incommensurable angle divided by the number of thread starts on the die, whereby said die may be interchangeably keyed to each one of said spindles in the predetermined angular relation to said thread start to assure proper phasing of the dies on the machine.

4. A circular thread rolling die adapted to be interchangeably applied to the spindles of an incommensurable angle thread rolling machine, said die having a spindle receiving bore therethrough and at least one thread start on its threaded periphery, said bore having a plurality of keyways positioned therein in predetermined angular relations to a thread start, the number of keyways in said bore being equal to the number of spindles in the thread rolling machine, one of said keyways being angularly located in relation to a thread start, the others of said keyways being displaced in relation to said first mentioned keyway and each other, the angular displacement in degrees being equal to the sum of twice the incommensurable thread rolling angle in degrees plus twice the incommensurable angle divided by the number of thread starts on the die, whereby said die may be interchangeably keyed to each one of said spindles in the predetermined angular relation to said thread start to assure proper phasing of the dies on the machine.

5. In combination, an incommensurable angle thread rolling machine having a plurality of spindles for receiving thread rolling dies, each of said spindles having a keyseat thereon, gearing revolubly connecting said spindles together in constant ratio, said gearing being connected to the spindles with the keyseat of each spindle in parallel axial planes to each other, a circular thread rolling die adapted to be detachably attached to each of said spindles, said die having a spindle receiving bore therethrough and at least one thread start on its threaded periphery, said bore having a plurality of keyways positioned therein in predetermined angular relations to a thread start, one of said

bore having a plurality of keyways positioned therein in predetermined angular relations to a thread start whereby the thread rolling die may be interchangeably keyed to each spindle and spindle keyseat at a predetermined angular relation to a thread start.

6. In combination, an incommensurable angle thread rolling machine having a plurality of spindles for receiving thread rolling dies, said spindles located in said machine with their axes in a common plane, each of said spindles having a keyseat thereon, gearing revolubly connecting said spindles together in constant ratio, said gearing being connected to the spindles with the keyseat of each spindle in parallel axial planes to each other, a circular thread rolling die adapted to be detachably attached to each of said spindles, said die having a spindle receiving bore therethrough and at least one thread start on its threaded periphery, said bore having a plurality of keyways positioned therein in predetermined angular relations to a thread start, one of said keyways being angularly located in relation to a thread start, the others of said keyways being angularly displaced in relation to said first mentioned keyway and each other by an amount which is a function of the incommensurable thread rolling angle and the number of thread starts on the die whereby the thread rolling die may be interchangeably keyed to each spindle and spindle keyseat at a predetermined angular relation to a thread start.

7. In combination, an incommensurable angle thread rolling machine having a plurality of spindles for receiving thread rolling dies, said spindles located in said machine with their axes in a common plane, each of said spindles having a keyseat thereon, gearing revolubly connecting said spindles together in constant ratio, said gearing being connected to the spindles with the keyseat of each spindle in parallel axial planes to each other, a circular thread rolling die adapted to be detachably attached to each of said spindles, said die having a spindle receiving bore therethrough and at least one thread start on its threaded periphery, said bore having a plurality of keyways positioned therein in predetermined angular relations to a thread start, the number of said keyways being equal to the number of said spindles, one of said keyways being angularly located in relation to a thread start, the others of said keyways being angularly displaced in relation to said first mentioned keyway and each other by an amount which is a function of the incommensurable thread rolling angle and the number of thread starts on the die whereby the thread rolling die may be interchangeably keyed to each spindle and spindle keyseat at a predetermined angular relation to a thread start.

8. In combination, an incommensurable angle thread rolling machine having a plurality of spindles for receiving thread rolling dies, said spindles located in said machine with their axes in a common plane, each of said spindles having a keyseat thereon, gearing revolubly connecting said spindles together in constant ratio, said gearing being connected to the spindles with the keyseat of each spindle in parallel axial planes to each other, a circular thread rolling die adapted to be detachably attached to each of said spindles, said die having a spindle receiving bore therethrough and at least one thread start on its threaded periphery, said bore having a plurality of keyways positioned therein in predetermined angular relations to a thread start, one of said

keyways being angularly located in relation to a thread start, the others of said keyways being angularly displaced in relation to said first mentioned keyway and each other, the angular displacement in degrees being equal to the sum of twice the incommensurable thread rolling angle in degrees plus twice the incommensurable angle divided by the number of thread starts on the die, whereby the thread rolling die may be interchangeably keyed to each spindle and spindle keyseat at a predetermined angular relation to a thread start.

9. In combination, an incommensurable angle thread rolling machine having a plurality of spindles for receiving thread rolling dies, said spindles located in said machine with their axes in a common plane, each of said spindles having a keyseat thereon, gearing revolubly connecting said spindles together in constant ratio, said gearing being connected to the spindles with the keyseat of each spindle in parallel axial planes to each other, a circular thread rolling die adapted to be detachably attached to each of said spindles, said die having a spindle receiving bore therethrough and at least one thread start on its threaded periphery, said bore having a plurality of keyways positioned therein in predetermined angular relations to a thread start, the number of said keyways being equal to the number of said spindles, one of said keyways being angularly located in relation to a thread start, the others of said keyways being angularly displaced in relation to said first mentioned keyway and each other, the angular displacement in degrees being equal to the sum of twice the incommensurable thread rolling angle in degrees plus twice the incommensurable angle divided by the number of thread starts on the die, whereby the thread rolling die may be interchangeably keyed to each spindle and spindle keyseat at a predetermined angular relation to a thread start.

10. In combination, an incommensurable angle thread rolling machine having a plurality of spindles for receiving thread rolling dies, each of said spindles having a keyseat thereon, gearing revolubly connecting said spindles together in constant ratio, said gearing being connected to said spindles with the keyseat of each spindle located in parallel axial planes to each other, a plurality of thread rolling dies adapted to be interchangeably attached to each of said spindles, the number of thread rolling dies being equal to the number of spindles, each of said dies having a spindle receiving bore therethrough and at least one thread start on its threaded periphery, said bore having a plurality of keyways therein, the number of said keyways being equal to the number of said spindles, each of said keyways being angularly located in relation to a thread start, and each of said keyways adapted to cooperate with a specified spindle keyseat whereby each of the dies may be interchangeably located on each of the spindles in the proper angular relation between the keyseat and thread start to assure accurate phasing of the dies.

11. In combination, an incommensurable angle thread rolling machine having a plurality of spindles for receiving thread rolling dies, each of said spindles having a keyseat thereon, gearing revolubly connecting said spindles together in constant ratio, said gearing being connected to said spindles with the keyseat of each spindle located in parallel axial planes to each other, a plurality of thread rolling dies adapted to be interchangeably attached to each of said spindles, the

number of thread rolling dies being equal to the number of spindles, each of said dies having a spindle receiving bore therethrough and at least one thread start on its threaded periphery, said bore having a plurality of keyways therein, the number of said keyways being equal to the number of said spindles, one of said keyways being angularly located in relation to a thread start, the others of said keyways being angularly displaced in relation to said first mentioned keyway and each other by an amount which is the function of the incommensurable thread rolling angle and the number of thread starts on the die, and each of said keyways adapted to cooperate with a specified spindle keyseat whereby each of the dies may be interchangeably located on each of the spindles in the proper angular relation between the keyseat and the thread start to assure accurate phasing of the dies.

12. In combination, an incommensurable angle thread rolling machine having a plurality of spindles for receiving thread rolling dies, each of said spindles having a keyseat thereon, gearing revolubly connecting said spindles together in constant ratio, said gearing being connected to said spindles with the keyseat of each spindle located in parallel axial planes to each other, a plurality of thread rolling dies adapted to be interchangeably attached to each of said spindles, the number of thread rolling dies being equal to the number of spindles, each of said dies having a spindle receiving bore therethrough and at least one thread start on its threaded periphery, said bore having a plurality of keyways therein, the number of said keyways being equal to the number of said spindles, one of said keyways being angularly located in relation to a thread start, the others of said keyways being angularly displaced from said first mentioned keyway and each other, the angular displacement in degrees being equal to the sum of twice the incommensurable thread rolling angle in degrees plus twice the incommensurable angle divided by the number of thread starts on the die, and each of said keyways adapted to cooperate with a specified spindle keyseat whereby each of the dies may be interchangeably located on each of the spindles in the proper angular relation between the keyseat and thread start to assure accurate phasing of the dies.

13. In combination, an incommensurable angle thread rolling machine having a plurality of spindles for receiving thread rolling dies, each of said spindles having a keyseat thereon, gearing revolubly connecting said spindles together in constant ratio, said gearing being connected to said spindles with the keyseat of each spindle located in parallel axial planes to each other, a plurality of thread rolling dies adapted to be interchangeably attached to each of said spindles, the number of thread rolling dies being equal to the number of spindles, each of said dies having a spindle receiving bore therethrough and at least one thread start on its threaded periphery, said bore having a plurality of keyways therein, the number of said keyways being equal to the number of said spindles, one of said keyways being angularly located in relation to a thread start, the others of said keyways being angularly displaced in relation to said first mentioned keyway and each other by an amount which is the function of the incommensurable thread rolling angle and the number of thread starts on the die, each of said keyways adapted to cooperate with a specified spindle keyseat, means on the die to

indicate the correct keyway to cooperate with a specified spindle keyseat, whereby each of the dies may be interchangeably located on each of the spindles in the proper angular relation between the keyseat and thread start to assure accurate phasing of the dies.

14. In combination, an incommensurable angle thread rolling machine having a plurality of spindles for receiving thread rolling dies, each of said spindles having a keyseat thereon, gearing revolvably connecting said spindles together in constant ratio, said gearing being connected to said spindles with the keyseat of each spindle located in parallel axial planes to each other, a plurality of thread rolling dies adapted to be interchangeably attached to each of said spindles, the number of thread rolling dies being equal to the number of spindles, each of said dies having a spindle receiving bore therethrough and at least one thread start on its threaded periphery, said bore having a plurality of keyways therein, the number of said keyways being equal to the number of said spindles, one of said keyways being angularly located in relation to a thread start, the others of said keyways being angularly displaced from said first mentioned keyway and each other, the angular displacement in degrees being equal to the sum of twice the incommensurable thread

rolling angle in degrees plus twice the incommensurable angle divided by the number of thread starts on the die, each of said keyways adapted to cooperate with a specified spindle keyseat, means on the die to indicate the correct keyway to cooperate with a specified spindle keyseat, whereby each of the dies may be interchangeably located on each of the spindles in the proper angular relation between the keyseat and thread start to assure accurate phasing of the dies.
